UNITED STATES PATENT OFFICE.

DANIEL W. COREY, OF GALENA, ASSIGNOR TO THE JUNE MANUFACTURING COMPANY, OF CHICAGO, ILLINOIS.

BOBBIN-WINDER.

SPECIFICATION forming part of Letters Patent No. 365,909, dated July 5, 1887.

Application filed February 2, 1886. Serial No. 190,605. (No model.)

To all whom it may concern:

Be it known that I, DANIEL W. COREY, a citizen of the United States, residing at Galena, county of Jo Daviess, and State of Illinois, have 5 invented certain new and useful Improvements in Bobbin-Winders, of which the following is a specification.

This invention relates to improvements in bobbin-winders especially designed for a bobbin having end flanges and sleeved upon a spindle provided with heads, between which the bobbin is confined.

The objects of this invention are to provide a bobbin-winder which shall center the bobbin and at the same time prevent the bobbin rotating upon its spindle, whereby the bobbin and its spindle shall revolve with and upon the axis of the shaft of the bobbin-winder.

A further object is to provide a bobbin-winder which shall not only center and prevent the bobbin turning on its spindle, but firmly hold the bobbin without exerting a crushing endwise strain thereon.

These objects are attained by devices illustrated in the accompanying drawings, in which—

Figure 1 illustrates a side elevation of a bobbin-winder embodying my invention, with a bobbin in its operative position therein; Fig. 2, an enlarged longitudinal sectional view of the same; Fig. 3, a similar and detail view of a modification in the construction of the actuating-shaft of the bobbin-winder; Figs. 4 and 5, end views of the bobbin shown in Figs. 35 1 and 2.

Similar letters of reference indicate the same parts in the several figures of the drawings.

Referring by letter to the accompanying drawings, A indicates the supporting bracket 40 or frame of an ordinary bobbin-winder secured to a machine by means of the lugs *a a* in the usual manner at any suitable point on the machine bed or arm. Loosely journaled in one end of this bracket is the ordinary spring-seated presser, B, having its operative end projecting toward the center of the said bracket, provided with a slight depression located centrally in the face thereof, and into which depression seats one end of the shaft of the bobbin, as will be hereinafter more fully described. 50 The construction of this presser is identical

with that common to devices of this character—that is to say, on the outer end of the shaft thereof is rigidly secured a thumb-piece, C, for withdrawing the head D of the presser 55 from contact with the bobbin-shaft, and also to limit the forward movement of the presser shaft and head when actuated by the spring-cushion. The end of the bracket is recessed to receive the said head D, which, as usual, is 60 of greater diameter than the presser-shaft, and surrounding this shaft, between the presser-head and the rear wall of the bracket, is located a spiral spring, E, for actuating the head and exerting a spring-tension longitudinally 65 on the end of the shaft of the bobbin. I may here add that the depression in the face of the head is for the purpose of centering and retaining the bobbin in position during the operation of winding.

In the opposite end of the bracket or frame is loosely journaled a short shaft, F, carrying upon its outer end the usual friction-wheel for imparting a rotary motion thereto, and having its inner end projecting beyond its bearing in the bracket enlarged to form a head, G, the said head and the friction-wheel serving to effectually prevent any endwise shifting of the shaft upon its bearing. This shaft is preferably hollowed or bored out to form a recess 80 for reception of a spindle, H, carrying upon its outer end a disk, I, working longitudinally in the enlarged annular recess J in the head G, as clearly illustrated in Fig. 2. Surrounding the spindle, and confined between 85 the disk I and an annular shoulder near the inner end of the recess, is a spiral spring, K, constituting a spring-cushion for the said disk I, against which one end and the opposite end to that engaging the presser of the bobbin-shaft bears.

To permit an endwise movement of the spindle H, and at the same time insure its rotation with the shaft F, the inner end of the said spindle has an elongated notch or offset, *c*, 95 into which projects and works a pin, *d*, which passes transversely through the shaft F, and is rigidly secured thereto. This pin, in connection with the notch, not only serves to insure the rotation of the spindle with the shaft, but 100 also permits an endwise movement of the said spindle in its socket, and at the same time

serves to limit the endwise movement of the said spindle, according to the length of the notch or offset *c*, and such limitation is necessary to prevent the disk *I* on the end thereof projecting beyond the face of the head *G*. I may here state, to give a clearer understanding of the operation of the notch *c* and pin *d*, that the face of the wall where the notch or offset is made is square or plain, and across this surface projects and works the pin; and it is obvious that any rotation of the shaft *F* will cause the pin to bear against one edge of the face of the notch, and thereby cause the spindle to rotate therewith.

15 Between the head *B* of the presser and the disk *I* is seated the bobbin-shaft *e*, carrying rigidly upon either end thereof flanges *ff*. The recess in the face of the head *B*, in which seats the end of the shaft *e*, serves to center said shaft on that end, while the flange on the opposite end of said shaft seats upon an annular shoulder, *g*, formed in the face of the head *G*, and is thereby readily centered on that end, thus avoiding the necessity for recessing the disk *I*.

20 Between the flanges *ff*, and loosely journaled upon the shaft *e*, is the bobbin *h*, upon which is wound the thread for the shuttle. The construction and operation of this bobbin are fully described and claimed in Letters Patent No. 323,916, granted to me August 11, 1885, and therefore does not enter as an element in this invention, and is only employed to illustrate the operation of my device, which 30 is especially designed for use in connection with bobbins constructed substantially in the manner just described—that is to say, a bobbin having end flanges and sleeved upon a spindle provided with heads between which the bobbin is confined.

35 The essential object of this invention is to prevent the bobbin rotating independently of its shaft or spindle during the operation of winding the bottom in such manner that the bobbin and its spindle shall revolve with and upon the axis of the shaft of the bobbin-winder. I am enabled to do this by employing a pin, *i*, rigidly secured to and projecting forward at a right angle from the face of the disk *I*, which pin passes through perforations or holes *j*, formed in the end flange of the bobbin and the flange on the shaft thereof. These holes must necessarily register with each other in order to permit the passage through them of the pin *i*, and they may be formed as two circular holes illustrated in Fig. 5, or preferably as illustrated in Fig. 4, in which is shown a circular hole, *j*, in the flange of the bobbin, with a series of elongated curved slots, *k*, formed in the flange *f* on the bobbin-shaft, and registering throughout their length with the hole *j*. The employment of these slots obviously facilitates the introduction of the pin into the hole *j*.

40 65 It will be observed by reference to Fig. 2 that the pressure or tension of the cushioning-spring both in the presser and the actuating-

shaft is exerted endwise upon the shaft of the bobbin, and therefore has no tendency whatever to crush or bend the flanges on said shaft, and thereby cause them to bind against the flanges of the bobbin; and with the central supports for the bobbin-shaft, as before described, the action of the pin on the face of the disk *I* would be in the nature of a crank-pin, and it is obvious that any rotation of the actuating-shaft carrying the spindle and disk will produce a corresponding rotation of the bobbin and shaft upon the axis of the said actuating-shaft and of the bobbin-winder as a whole.

70 In Fig. 3 I have illustrated a modification of my invention in which the actuating-shaft is solid and the pin *i* rigidly secured to and projecting from the face of the head *G*. The shaft of the bobbin seats in a corresponding recess or depression in the center of the face of said head, and is thereby centered and maintained in position. By this construction the end cushion of the bobbin, consisting of the spring-actuated disk *I*, may be dispensed with; but, as before described, the employment of such a cushion is advantageous in promoting a decrease in the endwise pressure on the bobbin, which tends to crush and strain 90 the said bobbin, and is therefore a preferred construction.

75 In conclusion, I may add that it would be no substantial departure from the spirit of my invention to provide a pin—that is to say, a crank-pin—projecting from the face of the presser-head, and dispense with the one on the actuating-shaft head; and it is thought that such a construction is so obviously within the scope of my invention that it is unnecessary 105 to illustrate this point in the drawings.

80 It is admitted that a swinging and solid shaft reciprocating in its bearing and held therein and made yielding by an angular spring pressing against its outer end has, before my invention, been provided with a crank-pin in its inner end; but this endwise yielding of the shaft renders the moving of the winder-pulley on the fly-wheel of the machine unstable and the actuation of the bobbin irregular and 110 uncertain, which objections are materially increased by the swinging feature of the entire structure; also, that a bobbin-winder in which a spring-actuated sleeve on the actuating-shaft, having its inner end closed, has, before 115 my invention, been provided with a crank-pin; but as such sleeve is between the shaft and the journal-box; and therefore subject to the entire friction of said box when the shaft is revolved, oil, dirt, grit, &c., not only accumulates in the spring-chamber and between the shaft and sleeve to such an extent as to 120 destroy the operation of the spring, but the friction between the sleeve and the box, when the bobbin is revolved at the ordinary but 125 high velocity, frequently causes a compression of the spring and an accidental discharge of the bobbin during the winding operation, and besides this, the yielding function of the shaft 130

promotes uncertain contact between the driving-wheel of the bobbin-holder and the fly-wheel of the machine, and to such an extent that if the driving-wheel is not thrown out of 5 contact its revolutions are extremely uncertain and irregular.

Having described my invention, what I claim, and desire to secure by Letters Patent, is—

- 10 1. In a bobbin-winder, a presser, in combination with a hollow actuating-shaft, a yielding disk provided with a crank-pin and confined and revolving in the said hollow shaft, and a spring, also confined within the shaft and actuating said disk, substantially as described.
- 20 2. In a bobbin-winder, a presser, in combination with a hollow actuating-shaft provided with a shoulder, *g*, for centering the bobbin, a yielding disk provided with a crank-pin and confined within and revolving with said shaft, substantially as described.
- 25 3. In a bobbin-winder, a presser, in combination with a hollow shaft, a yielding disk

provided with a crank-pin and confined and 25 revolving within said shaft, a spindle secured to said disk and a spring on the spindle actuating said disk, a pin, *d*, in the hollow shaft, and a notch in said spindle engaging said pin, whereby the disk may yield without a partial 30 rotation independent of the shaft, substantially as described.

4. In a bobbin-winder, a yielding presser and a spring actuating said presser, in combination with a hollow shaft, a yielding disk 35 provided with a crank-pin and confined and revolving within said shaft, a spindle secured to said disk and a spring on the spindle actuating said disk, a pin, *d*, in the hollow shaft, and a notch in said spindle engaging said pin, 40 whereby the disk may yield without a partial revolution independent of the shaft, substantially as and for the purpose described.

DANIEL W. COREY.
